Filed Nov. 15, 1965, Ser. No. 88,110

Term of patent 14 years

(Cl. D80—5)

FIG. 1 is a front elevational view of a display panel for cigarette lighters or similar articles showing our new design;

FIG. 2 is a plan view thereof;

FIG. 3 is a side elevational view thereof;

FIG. 4 is an enlarged fragmentary sectional view taken on line 4—4 of FIG. 1; and

FIG. 5 is an enlarged fragmentary sectional view taken on line 5—5 of FIG. 1.

The broken line showing of a cigarette lighter in FIG. 1 is for purposes of illustration only.

We claim:

The ornamental design for a display panel for cigarette lighters or similar articles, substantially as shown and described.
